UNITED STATES PATENT OFFICE.

HAROLD ROWNTREE, OF CHICAGO, ILLINOIS, ASSIGNOR TO THE BURDETT-
ROWNTREE MANUFACTURING COMPANY, OF SAME PLACE.

AUTOMATIC ELECTRIC ELEVATOR.

SPECIFICATION forming part of Letters Patent No. 638,281, dated December 5, 1899.

Application filed July 18, 1898. Renewed October 4, 1899. Serial No. 732,573. (No model.)

To all whom it may concern:

Be it known that I, HAROLD ROWNTREE, a citizen of the United States, residing at Chicago, in the county of Cook and State of Illinois, have invented a new and useful Automatic Electric Elevator, of which the following is a specification.

This invention relates to automatic electric elevators.

10 The object of the invention is to provide a construction and arrangement which is simple and efficient for automatically controlling the hoisting-motor of elevators from any floor or landing in the elevator shaft or well.

15 A further object of the invention is to provide means for controlling the starting of the hoisting-motor from any particular landing and automatically arresting the hoisting mechanism when the car reaches that particular landing.

A further object of the invention is to provide an apparatus wherein the speed of travel of the car in ascending and also in descending may be suitably regulated.

25 Further objects of the invention will appear more fully hereinafter.

The invention consists, substantially, in the construction, combination, location, and arrangement of parts, all as will be more 30 fully hereinafter set forth, as shown in the accompanying drawings, and finally specifically pointed out in the appended claims.

Referring to the accompanying drawings and to the various views and reference-signs 35 appearing thereon, Figure 1 is a front elevation of the hoisting mechanism. Fig. 2 is a side view of the same, the hoisting-motor shaft being shown in transverse section. Fig. 3 is a view, partly in side elevation and partly 40 in vertical section and upon an enlarged scale, showing the construction and arrangement of the motor-governing mechanism. Fig. 4 is a detail view showing the automatic controlling mechanism by which the elevator 45 hoisting mechanism may be thrown into action from any particular floor or landing past which the elevator-car travels. Fig. 5 is a detail sectional view on the line 5-5, Figs. 2 and 3, looking in the direction of the arrows.

50 Fig. 6 is a detail sectional view on the line 6-6, Figs. 2 and 3, looking in the direction of

the arrows. Fig. 7 is a detached detail face view, looking from the right, Figs. 2 and 3, of the contact-plate. Figs. 8 and 9 are detached detail views, in front and side elevations, respectively, of the brush-carrying bar. Fig. 10 is a diagram illustrating the wiring and electrical connections of the apparatus.

The same part is designated by the same reference-sign wherever it occurs throughout the several views.

In the accompanying drawings reference-sign A designates a suitable framework for supporting the various parts of the apparatus.

B is the hoisting-motor, and C the hoisting-motor shaft. This shaft, through any suitable form of coupling, (indicated at D,) is coupled to a shaft E, suitably journaled in the framework. Upon shaft E is mounted a worm-gear, (indicated in dotted lines at F, Fig. 2,) and which is arranged to intermesh with and to drive a worm-gear G, (also indicated in dotted lines in Fig. 2,) and which is mounted upon shaft H, upon which is mounted the hoisting-drum J for the car-hoisting cable. In suitable arms or brackets K L, mounted on framework A, is journaled a shaft M, to which rotation is imparted from shaft H in any suitable manner and by any suitable form of gearing through which a proper speed reduction is secured. In the form shown, to which the invention is not limited, I show a train of intermeshing gears N, Fig. 2, so relatively proportioned as to size and arrangement as in practice to impart to shaft M something less than one-half a complete revolution during the rotations of shaft H, necessary to move the elevator-car from one of its extreme limits of travel to the other. The invention, however, is not limited in this respect, as any other suitable or desirable relative speeds may be imparted to shafts H and M. Suitably mounted on and pinned, as at 12, to rock with shaft M is a bar 13, in the outer or free end of which is pivotally mounted at the angle thereof a peculiarly-shaped angular bar or lever 14, the pivot being indicated at 15. This angle-lever 14 is preferably in the form of a double crank, as clearly shown in Fig. 3, and on one of the free ends thereof carries an antifriction-roller 16, arranged to travel over the peripheral surface of a plate

17, suitably bolted or otherwise secured to the standard or bracket K or other convenient part of the framework. This plate 17 is provided in the peripheral surface thereof with 5 depressions or seats 18, corresponding in number to the number of floors or landings at which the elevator is designed to stop and into which, as will hereinafter more clearly appear, the roller 16 is adapted to be received 10 at the proper time. In order that said roller may easily ride into and out of the seats or depressions 18, the walls of such seats or depressions are suitably curved, as most clearly shown in Figs. 1 and 5. Also carried by the 15 same arm of crank-lever 14 is a pin 19, (see Fig. 5,) arranged to travel over the peripheral edge or surface of a disk or plate 20, mounted upon shaft M, but capable of slight rotative movement thereon, as will presently more 20 clearly appear. The peripheral edge of plate 20 is provided with notches or recesses 21, corresponding in number and arrangement to the depressions or seats 18 in plate 17, and into which at the proper time the pin 19 is 25 adapted to be received. The walls of notches or recesses 21 are squared, as clearly shown in Fig. 5, in order that when the parts are brought into suitable relation for pin 19 to be received in one or the other of said notches 30 or recesses 21 such pin will enter the notch or recess quickly and with a snapping action.

From the foregoing description it will also be seen that the roller 16 will not be permitted to drop into its depression or recess 18 35 until pin 19 is brought into register with a peripheral notch 21 in the edge of disk 20; but when such register is secured both the roller 16 and the pin 19 will snap quickly into their respective notches or seats. The angle-lever 40 14, which for want of a better term I shall hereinafter designate the "kicker," is acted upon by springs 22, fixed at one end to bar 13 and at the other end connected to said kicker, the tension of said springs being ex- 45 ereted in a direction to constantly maintain pin 19 and roller 16 in engagement with the peripheries, respectively, of plates 17 and 20, and through these springs the quick-snapping action of pin 19 and roller 16 into their 50 respective notches or recesses is secured when the parts are brought into their proper relative arrangement therefor.

I have above stated that disk or plate 20 is mounted on shaft M for slight rotative movement thereon. Said plate is guided during such rotative movement by means of a pin 23, fixed in the bracket K or other convenient part of the framework and projecting through an elongated slot 24 (see Fig. 5) in 55 said plate or disk. It is important to provide means whereby the disk 20 is normally held in centered position. I have shown an efficient arrangement for accomplishing the centering of this plate or disk and for returning the same to its centered position when said disk or plate is rotatively depressed in either direction. This centering arrange- 60

ment is shown most clearly in Figs. 3 and 5, wherein arms 25 26 are pivotally mounted on plate or disk 20 and on opposite sides of pin 23 and in close proximity to such pin. A stout spring 27 is connected at one end to the free end of arm 25 at a point such as to bring pin 23 between the same and the point of pivotal connection of said arm 25. This spring 75 is connected at its other end to a suitable lug or otherwise to said disk or plate 20 at a point on the opposite side of pin 23 from said arm 25. In a similar manner a spring 28 is connected at one end to the free end of arm 26 80 and at its opposite end to the disk or plate 20 at a point on the opposite side of pin 23 from said arm 26. From this construction it will be seen that the tension of said springs is constantly exerted to swing said arms 25 85 26 into contact with the sides of pin 23. Therefore when said disk or plate 20 is rotatively moved such rotative movement is yieldingly opposed by the tension of one or the other of said springs 27 28, which tension tends to return said plate or disk to centered position. In order that when a rotative movement is imparted to said disk or plate 20 in a direction to distend one of said springs the other of said springs may not contract or follow up 90 the distended spring, I have provided a pin 29 in the face of said plate or disk and which is arranged to project between the ends of arms 25 26, thereby preventing one of said springs from contracting during the distension of the other, and hence rendering more reliable the action of the centering arrangement to always return said plate or disk to its centered position when rotatively displaced from such normal or centered position. 95

Loosely mounted on shaft M, adjacent to the bar 13, is a disk 30, upon which are mounted in concentric circles the contact-rings 31 32. These contact rings are preferably semi-circularly divided, as clearly shown in Fig. 7, 100 and these sections are insulated from each other and are cross-connected electrically—that is to say, the inner contact-ring 32 on one side or half of disk 30 is electrically coupled to the outer contact-ring on the other 105 half of said disk, the cross connections being shown in dotted lines at 33, Fig. 7. The brushes 34 35 (see Fig. 3) are arranged to respectively make electrical contact with the inner and outer segments or sections 31 32. 110 These brushes are mounted upon or carried by a bar 36, pivotally mounted at one end thereof, as at 37, upon an arm or bar 38, loosely sleeved upon shaft M, as clearly shown in Figs. 3 and 6. The axis or pivot 37, about 115 which brush-carrying arm 36 swings, is arranged parallel with the face of contact-carrying disk 30. Therefore when brush-carrying arm 36 is rocked about its pivot or axis such rocking movement is in a direction to carry 120 brushes 34 35 toward or away from the contact rings or segments 31 32 to make or break the circuit of the hoisting-motor, as will presently more fully appear. A pin 39 is mount- 125

ed in bar 38 and projects loosely through brush-carrying arm 36, as at 40, Fig. 9. A spring 41 is mounted on said pin and interposed between bar 38 and brush-arm 36, the 5 action of said spring being to yieldingly press brush-carrying arm 36 in a direction for the brushes 34 35 to be pressed against and into contact with contact rings or segments 31 32, but permitting such arm 36 to be rocked or 10 swung about its pivot and in a direction such as to break electrical contact between said brushes and rings. In order to steady and guide brush-carrying arm 36 during the swinging movements thereof about its pivot 37, bar 38 is provided with a projecting end 42, (see Figs. 3 and 6,) arranged to project into a notch or recess 43, formed in brush-carrying arm 36. (See Fig. 9.)

As above stated, contact-carrying disk 30 20 is mounted loosely on shaft M. Said disk is provided with an elongated slot 44, through which passes a pin 45, projecting from bar 13, which, as above stated, is mounted on to rotate with shaft M. This pin 45 serves as a 25 guide for disk 30 and causes the rotation of said disk coincident with the rotation of shaft M, with a desirable range of lost motion within the limits of the extent of slot 44.

The brush-carrying arm 36 is provided with 30 a flange 46, and one of the crank ends 47 of kicker 14 is arranged to project through a slot or opening 48 in disk 30 and into position to engage at the proper moment flange 46 in a direction to rock or swing brush-arm 36 about its pivot 37 against the action of 35 spring 41, and therefore in a direction to cause brushes 34 35 to leave contact-segments 31 32. This engagement between the end 47 of kicker 14 and flange 46 of brush-carrying arm 36 is 40 not effected, however, until the parts are brought into such relative position that roller 16 and pin 19 on the other crank end or arm of kicker 14 are snapped into the notches or recesses 18 21 of disks 17 20; but the snapping 45 of said roller and pin into said notches or recesses causes a quick projection of arm 47 endwise against flange 46, thus quickly effecting a breaking of contact between brushes 34 35 and contact-rings 31 32. When kicker 50 14 is returned to its normal position, thereby withdrawing its arm 47 from its projected position, spring 41 will operate to restore brush-arm 36 to its normal position with brushes 34 35 contacting with contact-rings 31 32. It

55 is important that flange 46 of brush-arm 36 be brought squarely and directly in line with the end of kicker-arm 47, so as to be efficiently and accurately engaged thereby when said kicker-arm is projected. To attain this result, I provide in the face of disk 30 a pin 49, arranged to project into the rotary path of flange 46 when arm 36 is carried around the axis of the sleeve of bar 38 by the rotation or rocking movement of said bar 38. These 60 parts are so relatively arranged that when the face of flange 46 engages the side of pin 49 the end of kicker-arm 47 will be directly

in alignment with the center of the flange 46, and hence in position to efficiently engage such flange and rock the brush-arm in a direction to break circuit between brushes 34 35 and rings 31 32. Pin 49 also serves another purpose. It prevents reversal of the motor when it is once set in operation until after it has completed its work of carrying 75 the car to a predetermined point and brought the car to rest. The reason for this is that so long as the parts are in position to make contact between brushes 34 35 and rings 31 32 said pin 49 operates as a back-stop to prevent reverse rotation of arm 36 about shaft M, thus also locking bar 38 against reverse rotation on said shaft, but permitting said bar 38 to rotate in the forward direction. The pin 49 is of such length, however, that 80 when kicker-arm 47 has been projected in a direction to rotate brush-arm 36 away from the position thereof in which brushes 34 35 contact with rings 31 32 the flange 46 of said brush-arm 36 will clear pin 49, and hence 85 permit arm 36, and hence also bar 38, to rock or swing in a reverse direction or freely in either direction around shaft M. This, however, is not permitted until kicker 14 has operated to break the motor-circuits, and as 90 this kicker is not adapted to operate except and until the car reaches its predetermined destination it will be seen that pin 49 operates as a stop or lock to prevent undesirable actions of the motor or reversals thereof after 95 once being set in operation until it has completed the task of moving the car to the point predetermined at the time it was set in operation; but when such destination is reached and the kicker 14 operates reversal of the 100 motor can thereafter be effected.

Suitably connected to bar 38, but preferably at right angles with reference thereto, is an operating or controlling bar 50. This bar is also sleeved to rock loosely upon shaft 110 M and is connected to rock with bar 38. To one end of lever 50 is connected a rod 51, (see Fig. 4,) by which said lever may be rocked. Suitable stops or lugs 52 on said lever are provided and arranged to engage the bracket L 115 to limit the movement thereof. Through the rocking of lever 50, and with it bar 38, whereby said parts rock or swing about the axis of shaft M, the control of the hoisting mechanism is effected.

The operation of the apparatus so far described is as follows: Suppose the car to be at its bottom limit of travel and the mechanism in its normal position of rest and it is desired that the car ascend to the first floor, 125 for instance. Lever 50 is rotated to the desired point, as will presently be more fully explained, thereby rocking bar 38 and with it swinging brush-carrying arm 36 axially about shaft M to a position determined by the position to which lever 50 is rocked, and this position is determined according to the particular floor to which it is desired to send the elevator-car. If in this position of rest, in which

we have assumed the parts to be at the beginning of the operation, the kicker 14 has been actuated to project endwise the arm 47 thereof, it will be understood from the foregoing description that brush-carrying arm 36 will have been rocked or swung about its pivot 37, so as to break contact between brushes 34 35 and rings 31 32, and hence said bar 36 will be held in a position permitting it to swing or rock freely past the fixed pin 49. As soon as said brush-arm 36 has cleared the end of arm 49 spring 41 will come into play and will rock arm 36 in a direction to cause brushes 34 35 to again make contact with rings 31 32, thereby completing the motor-circuit and starting up the motor. By the rotation of shaft M through gearing N, as above described, and by reason of the curved or semicircular walls of recesses 18 in plate 20 or disk 17 roller 16, which is carried by kicker 14 and which in turn is mounted upon and is carried by bar 13, will be dragged out of the recess or seat 18, in which it rested at the beginning of the operation. Thus kicker 14 will be gradually rocked about its pivot 15 and in a direction to withdraw the arm 49 thereof from its previously-projected position. The slow rocking of kicker 14 by reason of the drag of roller 16 out of its recess 18 necessitates the mounting of disk 20 for slight rotative movement, which is secured through pin 23 projecting through slot 24, for the reason that pin 19, carried by kicker 14, is seated, under the conditions obtaining at the beginning of the operation, in the square-walled notches or recesses 21, and therefore cannot be dragged out of such notches or recesses in the manner in which roller 16 is dragged out of its notch or recess; but by providing the relative rocking or rotation of disk 20 it will be seen that the complete withdrawal of roller 16 from its initial seat or depression 18 will also finally effect the withdrawal of pin 19 from its square notch or recess 21; but when said pin 19 is withdrawn from its notch or recess 21 the springs 27 28 operate to always return or center said disk 20. The kicker is thus again held in position to automatically effect a breaking of the motor-circuits. It will be remembered, however, that brush-arm 36 has been rotated to a point corresponding to the particular floor at which it is desired to stop the elevator-car. This position also corresponds to the position of a coöperating pair of notches or recesses 18 21. If the position at which the car is to be stopped is the first floor from the point where the car started, it will be seen that when roller 16 and pin 19 come in register with the notches or recesses 18 21 corresponding to such floor the kicker 14 will be snapped, as before explained, thereby projecting the end of the arm 47 thereof into engagement with brush-arm 36, thereby automatically breaking the motor-circuits. Before this point is reached, however, flange 46 has come in contact with pin 49, thereby

insuring that the edge of flange 46 is presented in true alinement with the end of arm 47. If, however, it be desired to send the car in the first instance to the second or third floor instead of the first, it will be seen from the foregoing description that when the kicker 14 is actuated at the first floor it will not find brush-arm 36 in line with the end of the arm 47 thereof, because such arm 36 has been swung to a position corresponding with some other floor or landing. Therefore the action of the kicker at the first floor will be without result and the motor will continue to operate, thus causing, in the same manner as above described, the kicker 14 to be restored to its initial or kinetic position by the roller 16 thereof being dragged out of the seat or depression 18, into which it dropped when the car reached the first floor, and so at the second landing, if it has not been previously determined to arrest the car at such landing, the kicker will again automatically operate, but without result, and the motor will continue to operate until finally the car reaches the floor which has been previously determined upon as its stopping-place, and when such floor is reached by the car the kicker will automatically operate and this time will find brush-arm 36 and will automatically effect an arresting of the hoisting mechanism, leaving the parts in position to be actuated to return the car to its original position or to continue to some floor or landing above.

Many suitable arrangements may be provided whereby lever 50 may be actuated from any floor or landing. While, therefore, I have shown and will now describe a specific construction whereby the proper actuation of said lever may be effected from any particular floor, I desire it to be understood that the invention is not limited or restricted thereto.

In the particular form shown lever 50 is connected through a rod 51 with a crank-arm 52^a, mounted upon and to revolve with a shaft 53. Upon this shaft is mounted a sprocket-gear 54, around which and a similar sprocket-gear 55 is arranged to pass in an open bight a sprocket-chain 56. The sprocket-gears 54 55 are respectively arranged at the top and bottom of the elevator shaft or well, and therefore sprocket-chain 56 extends in an open bight throughout the length of the elevator shaft or well. If desired and in order to maintain suitable tension on sprocket-chain 56, the sheave 55 at the bottom of the shaft or well may be suitably weighted, as at 57.

At each floor is arranged a sprocket-gear 58, arranged to mesh with one leg or run of sprocket-chain 56, and mounted on the shaft of each of said gears 58 to revolve therewith is a pointer 59, arranged to operate in connection with a dial-plate 60, each having notches, numerals, or other indices corresponding to the number of landings at which the car is intended to stop. The operation of this feature of the invention is as follows: If it is desired to start the car-hoisting mechanism and to ar-

rest the car at any particular floor, a person at that floor will operate the pointer 59, so as to bring the same into line with the proper number or mark on the dial corresponding to that 5 floor. This will effect an actuation of sprocket-chain 56 and a corresponding actuation of the pointers of all the dials throughout the system, so that the position of the car may be indicated at each landing of the elevator-shaft. 10 The actuation of sprocket-chain 56 effects a rotation of sprocket-wheel 54 and shaft 53, thereby rocking crank-arm 52^a, and hence effecting a swinging of lever 50 to a position corresponding to the particular floor at which it 15 is desired to arrest the car.

Any suitable braking appliance may be employed in connection with the hoisting-motor. In practice, however, I prefer to employ a strap-brake of ordinary type, which may be 20 applied to the coupling-disk D, as indicated in Fig. 1, and preferably I employ a solenoid P for actuating said strap-brake, and in practice I include the coils of said solenoid directly in the motor-circuit, so that whenever 25 a motor-circuit is broken the brake will always be applied and, on the other hand, whenever the motor-circuit is closed the brake is released.

Many specifically different forms and constructions of brake-magnet and brake would 30 readily suggest themselves to persons skilled in the art, and therefore as such construction does not in the specific details and arrangements thereof form or constitute the present 35 invention I have not deemed it necessary to specifically illustrate or describe the same herein.

I will now describe the arrangement of the 40 electrical wiring of the motor, particular reference being had to Fig. 10.

The main supply-conductor 61 leads from any suitable connection or wall-switch 62, for instance, to binding-post 63 and thence through conductor 64 to brush 34. The conductor 45 ducting-segment 31 on the right-hand side of the contact disk or plate 30 and which is cross-connected electrically with the inner contact-segment 32 on the left-hand side of such disk or plate is connected by conductor 65 with a 50 binding-post 66 and from thence through conductor 67 with one brush of the motor-armature. Thence circuit is continued through the armature-windings, the other brush of the armature, and by way of conductor 68 to binding-post 69. This binding-post is connected 55 through conductor 70 to the outer contact-segment 31 on the left-hand side of the contact-disk, which segment is cross-connected to the inner segment 32 on the right-hand side 60 of said disk. Brush 35 is connected through conductor 71 with binding-post 72 and thence through conductor 73 with one terminal of the motor-field coils. Thence circuit is completed through such coils and through conductor 74 to binding-post 75, which is connected through conductor 76 with one terminal of the windings of the brake-magnet or

solenoid. The other terminal of the windings of said magnet or solenoid is connected through conductor 77 with binding-post 78, 70 which is connected through conductor 79 to the return-wire. The field resistance is included in the circuit with the connection 80, leading from binding-post 69, and conductor 81, leading to binding-post 72. An armature 75 resistance is connected through conductor 82 to binding-post 83 and through conductor 84 with binding-post 75. Binding-post 83 is connected through conductor 85 to a brush 86, arranged in contact with a conducting-segment 87 on the contact disk or plate 30, as clearly shown in Figs. 3 and 10. This auxiliary contact-strip 87 is arranged only on one side of contact-disk 30, as shown, and is in electrical connection with the contact-strip 31 85 on the same side of said disk 30 therewith and the function of which will presently be more fully explained.

In the foregoing description I have traced the various electric circuits, and from this description it will be seen that the main or positive supply-conductor 61 is directly connected to brush 34 and that the return-conductor 79 is directly connected to one end of the coils of the solenoid or magnet. From this it will 95 be seen that when the motor-circuit is completed the solenoid or brake-magnet will always be energized and the brake liberated, and when the motor-circuit is broken the brake will be set. 100

I will now explain the electrical operation. When a pointer 59 is moved to any particular point or landing at which it is desired to arrest the car, circuit is established through the operation above described of the motor-controlling apparatus as follows: through supply-conductor 61 to binding-post 63, conductor 64, brush 34, contact-segment 31, conductor 65, binding-post 66, conductor 67, through the coils of the motor-armature, conductor 68, binding-post 69, conductor 70, segment 31 on the opposite side of the contact-disk 30, and which is connected electrically to the inner contact-segment 32 on the right-hand side of the contact-disk; but since auxiliary contact-segment 87 on the left-hand side of the contact-disk, as seen in Figs. 7 and 10, is in electrical connection with contact-segment 31 on the same side of the contact-disk it will be seen that current at this point and arriving 105 through conductor 70 will divide into two branches, one of which includes brush 35, conductor 71, binding-post 72, conductor 73, the coils of the motor-field windings, conductor 74, binding-post 75, conductor 76, the windings of the brake-magnet or solenoid, conductor 77, and binding-post 78 to return-wire 79. The other path or branch includes the extra or auxiliary brush 86, which is in contact with segment 87 only when the car is traveling upwardly, thence through conductor 85, binding-post 83, conductor 82, the armature resistance, conductor 84, binding-post 75, conductor 76, and on to return-wire 79, through 110 115 120 125 130 135

the same path as that above described with reference to the first-mentioned branch. From this description it will be seen that when the car is going up not only does all the current which flows through the motor-field windings also flow through the armature-windings of the motor, but, in addition thereto, the current which passes through the armature resistance also passes through the armature, thereby augmenting the power of the motor. If the armature resistance should be so great that no current will flow therethrough through the shunt or branch circuit above described, then the current passing through the motor-armature windings would be the same as that which passed through the field-windings of the motor, and hence the motor would have nearly its ordinary strength. It will also be seen that the less resistance in the auxiliary circuit, which includes conductors 82 and 84, the greater would be the difference between the currents flowing through the motor-field windings and the motor-armature windings—that is to say, the greater would be the amount of current flowing through the armature-windings relative to that which flows through the field-windings, and hence the greater would be the power developed by the motor. By this arrangement, whereby all the current which passes through the field of the motor also passes through the armature of the motor, it will be seen that I am enabled to quickly disrupt the motor-circuits—as, for instance, by the snapping action of kicker 14—for the reason that only a fixed amount of current can flow through the armature resistance, and therefore any undue rush or flow of current through the armature will also flow through the field.

It will be remembered, of course, that in the foregoing description of the electrical operation we have assumed that the car is traveling upwardly. Now when a pointer 59 is moved for the purpose and in a direction to cause the car to descend the circuit is completed as follows: from the main supply-conductor 61 to brush 34, as before, which is now while the car is descending in contact with segment 31 on the left-hand side of contact-disk 30, thence through conductor 70 to binding-post 69, where the circuit divides, part flowing through conductor 68, the brush of the motor-armature on the opposite side to that above described, thence through the motor-armature windings, the other motor-armature brush, conductor 67, binding-post 66, conductor 65 to contact-segment 31 on the right-hand side of disk 30, to the segment 32 through connection 33, to brush 35, which, under the conditions now being described, has been shifted to the left from the position shown in Fig. 10, thence through conductor 71, binding-post 72, conductor 73, the windings of the motor-field magnets in the same direction as before described when the car was ascending, thence through conductor 74, binding-post 75, conductor 76, and on through the coils of the brake-magnet or solenoid to return-conductor 79. The other branch of the circuit leads from binding-post 69 through conductor 80, the motor-field resistance, conductor 81 to binding-post 72, thence on through conductor 73, the motor-field windings, and conductors 74 and 76, as above described. Thus it will be seen that when the car is going down all the current that passes through the motor-armature windings also passes through the motor-field coils, and, in addition to this, that portion of the current which passes through the motor-field resistance also passes through the motor-field, thereby increasing the amount of current flowing through the field relative to the current which is flowing through the motor-armature. The effect of this is to retard the speed of the motor by creating a large or strong field with small current in the armature. In other words, the motor will act on the order of an electric brake. Of course if the field resistance is sufficiently great to prevent current flowing therethrough then the same amount of current that passes through the field would also pass through the armature, and hence the motor would run at its ordinary speed, or at a much higher rate of speed in case the elevator-car is heavily loaded and is descending, by reason of gravity acting upon the load on the car. It will also be seen that the smaller the amount of resistance in the field-circuit the smaller will be the current which flows through the armature in proportion to that which passes through the motor-field, because the field-resistance circuit, which is in shunt around the armature, will offer less resistance to current flowing therethrough, and hence by the foregoing arrangement it will be seen that I am enabled to suddenly make or break the motor-circuit while the car is descending without injurious results, because any rush of current in starting the motor is taken care of by the field-wiring.

It is believed that from the foregoing description persons skilled in the art will readily understand and comprehend the construction, function, and mode of operation of the apparatus.

Having now set forth the object and nature of my invention and a form of apparatus embodying the same and having described a construction, function, and mode of operation of such apparatus, I desire it to be understood that the invention is not limited or restricted to the exact details shown and described, as many changes therein and variations therefrom would readily suggest themselves to persons skilled in the art and still fall within the spirit and scope of my invention; but

What I do claim as new and useful and of my own invention, and desire to secure by Letters Patent of the United States, is—

1. In an automatic elevator, a hoisting-motor, a controlling mechanism therefor, a dial marked for the different landings, a manu-

- ally-actuated pointer for said dial, and mechanical connections between said pointer and controlling mechanism whereby when the pointer is moved to any particular mark on the dial the motor will be started and automatically arrested when the car reaches the particular floor corresponding to the mark on the dial, as and for the purpose set forth. 5
2. In an automatic elevator, a hoisting-motor, a controlling mechanism therefor, said controlling mechanism including a switch, a dial, a pointer therefor and connections between said pointer and controlling mechanism whereby when said pointer is moved said motor is started and said switch is set to position corresponding to the position of the pointer, thereby automatically arresting the motor when the car reaches the particular floor corresponding to the position of the 10 pointer on the dial, as and for the purpose set forth. 15
3. In an automatic elevator, a hoisting-motor, a switch therefor, means for operating said switch to arrest the motor when the car reaches each landing, and means controllable from any floor or landing for setting said switch in coöperative relation with respect to said operating means whereby said switch will be automatically operated to arrest said motor only when the car reaches a particular predetermined landing, as and for the purpose set forth. 20
4. In an automatic elevator, a hoisting-motor, a controller therefor, and mechanical connections arranged to be actuated from any landing for operating said controlling mechanism, whereby said motor may be started automatically from any landing and arrested when the car reaches that landing, said connections including means for indicating the location of the car, as and for the purpose set forth. 25
5. In an automatic elevator, a hoisting-motor, a controlling-switch therefor, and manually-operated means arranged at each landing at which the car stops for setting said switch and starting the motor, whereby the motor will be arrested when the car reaches the particular floor for which the switch was set, as and for the purpose set forth. 30
6. In an automatic elevator, a hoisting-motor, a controlling-switch therefor, a dial arranged at each landing at which the car stops and marked for the different landings, a pointer for each dial, and common connections between all of said pointers and said switch, whereby when the pointer at any particular floor is moved to the mark on the dial corresponding to any floor the motor will be started 35 and arrested automatically when the car reaches that particular floor, as and for the purpose set forth. 40
7. In an automatic elevator, a hoisting-motor, a controlling-switch therefor, a dial arranged at each landing at which the car stops, a pointer for each dial, and means actuated by the movements of the pointer at any 45
- ticular floor for actuating said switch to complete the motor-circuit for starting said motor, said means also operating to set said switch to position corresponding to the floor indicated by said pointer, whereby the motor will be automatically arrested when the car reaches that particular landing, as and for the purpose set forth. 50
8. In an automatic elevator, the combination with a hoisting-motor, a controlling-switch therefor, a dial, a manually-operated pointer associated with said dial, and connections between said pointer and switch, and actuated by the movement of said pointer for starting said motor and arresting the same automatically at a predetermined point, as and for the purpose set forth. 55
9. In an automatic elevator, the combination with an electric hoisting-motor, circuits therefor, a switch for controlling said circuits, a dial arranged at each floor, a pointer for each dial, connections between each pointer and said switch for setting the latter, and means for automatically operating said switch to break the motor-circuit when the car reaches the particular floor indicated by the pointer, as and for the purpose set forth. 60
10. In an automatic elevator, an electric hoisting-motor, a dial arranged at each floor or landing, a manually-actuated pointer co-operating therewith, a switch for controlling the circuits of said motor, and means controlled by the movements of said pointer for automatically opening said switch as soon as the car has arrived at the landing corresponding to the position of the pointer on the dial, as and for the purpose set forth. 65
11. In an automatic elevator, the combination with an electric hoisting-motor, circuits therefor, a controlling-switch for said motor, a dial arranged at each landing, a pointer for each dial, connections between each pointer and said controlling-switch for setting the latter at any predetermined point, whereby the motor-circuits are broken automatically when the car arrives at the landing corresponding to the position of the pointer on the dial, as and for the purpose set forth. 70
12. In an automatic elevator, a hoisting-motor, means controllable from each landing for setting said motor in operation, said controllable means being connected to operate in unison, whereby the location of the car is indicated at each landing, a lever arranged to be rocked when the car reaches each landing, and means whereby said lever automatically arrests the motor only when the car reaches a particular predetermined landing, as and for the purpose set forth. 75
13. In an automatic elevator, a hoisting-motor, a switch therefor, a lever, means for rocking said lever only when the car reaches each landing, a dial, a pointer located at each landing for setting said switch in coöperative relation with respect to said lever, said several pointers being connected to operate in unison, whereby when the car reaches a pre- 80

determined landing said lever will actuate said switch to arrest said motor, and the position of the car will be indicated on each dial, as and for the purpose set forth.

14. In an automatic elevator, a hoisting-motor, a controlling-switch therefor, a pivotally-mounted lever, a disk having notches or recesses corresponding to the several landings at which the car stops and into which the end of said lever is received, whereby when the car reaches each landing said lever is rocked, and means controllable from each landing for setting said switch in the path of said lever to be actuated thereby when the end of said lever drops into any one of the notches to break the motor-circuits only when the car reaches a predetermined landing, as and for the purpose set forth.
15. In an automatic elevator, a hoisting-motor, a disk provided with a plurality of seats or depressions corresponding in their relative positions to the different landings of the elevator-shaft, a lever arranged to be drawn into or out of said seats or depressions, a motor-switch, arranged to control the hoisting-motor, and means controllable from each landing for setting said switch, whereby said lever will automatically open said switch only when the car reaches a predetermined landing, as and for the purpose set forth.

16. In an automatic elevator, the combination of a hoisting-motor, circuits therefor, a dial arranged at each landing of the elevator-shaft, a pointer coöperating with each dial, a switch for said motor, connections common to all of said pointers and extending to said switch to set the latter, a pivotally-mounted lever arranged to be rocked when the car reaches each landing, and means whereby the rocking of said lever will automatically open said switch only when the car reaches the landing corresponding to the position of the pointer, as and for the purpose set forth.

17. In an automatic elevator, a hoisting-motor, a dial arranged at each floor, a pointer coöperating with each dial, a controller for said motor, connections between each pointer and said controller, a pivotally-mounted lever, a disk provided with a series of seats or depressions corresponding in their relative positions to the different landings of the elevator-shaft, said lever arranged to be drawn into said seats or depressions when the car reaches each landing, and means whereby said lever automatically actuates said controller to arrest said motor when the car reaches the particular landing corresponding to the position of the pointers, as and for the purpose set forth.

18. In an automatic elevator, a hoisting-motor, a counter-shaft driven thereby, an arm mounted on to revolve with said counter-shaft, a lever pivotally mounted on said arm, means for rocking said lever when the car reaches the landing, a switch for said motor, and means controllable from each landing for

setting said switch in the path of said lever, whereby said switch is automatically actuated when the car reaches a predetermined landing, thereby arresting the action of said motor, as and for the purpose set forth.

19. In an automatic elevator, a hoisting-motor, a counter-shaft driven thereby, an arm mounted on to revolve with said counter-shaft, a lever pivotally mounted on said arm, a fixed disk, springs for yieldingly maintaining said lever in peripheral contact with said disk, seats or depressions formed in said disk and corresponding to the various floors at which the car stops, a controller for said motor, means arranged at each floor or landing for setting said controller in the path of action of said lever and corresponding to each floor, whereby when the car reaches any predetermined landing said controller will be actuated and the motor arrested, as and for the purpose set forth.

20. In an automatic elevator, a hoisting-motor, a counter-shaft driven thereby, an arm mounted on said counter-shaft, a lever pivotally mounted on said arm, a fixed disk, means for yieldingly maintaining peripheral contact between said lever and disk, said disk provided with seats or depressions having inclined walls corresponding in relative arrangement to the several landings at which the car stops, a second disk having squared sockets or notches, a pin carried by said lever adapted to be received in said notches or sockets, said notches or sockets corresponding in relative arrangement to the seats or depressions in said first-mentioned disk, a controller for said motor, means actuated from each landing for setting said controller in the path of action of said lever, as and for the purpose set forth.

21. In an automatic elevator, a hoisting-motor, a switch therefor, means actuated from each landing for setting said switch, in combination with a counter-shaft driven from said motor, an arm mounted thereon, a lever pivotally mounted on said arm, a fixed disk having peripheral seats or depressions, springs for yieldingly maintaining said lever in contact with the periphery of said disk, the seats or depressions in said disk having inclined walls, a second disk movably centered on said counter-shaft and provided with squared notches or recesses in the periphery thereof, a pin carried by said lever and having peripheral contact with said movable disk, and means for yieldingly maintaining said movable disk in centered position, as and for the purpose set forth.

22. In an automatic elevator, a hoisting-motor, a lever, means for rocking said lever when the car reaches each landing, a switch-arm for controlling the circuits of said motor, means controllable from each landing for moving said arm into the path of movement of said lever, whereby when the car reaches a predetermined floor said arm will be actu-

ated to arrest said motor, and means for locking said arm against reverse movement while the motor is in operation, as and for the purpose set forth.

5 23. In an automatic elevator, a hoisting-motor, circuits therefor, a disk carrying contacts arranged in said circuits, a bar mounted to rotate, a brush-arm pivotally mounted on said bar and normally held in position for the 10 brushes thereon to contact with the contacts on said disk, means controllable from each floor or landing for rocking said bar, and means for automatically rocking said brush-arm to break the circuits of the motor when 15 the car arrives at any predetermined landing, as and for the purpose set forth.

24. In an automatic elevator, a hoisting-motor, circuits therefor, a disk carrying contact-segments included in said motor-circuits, 20 a rotatable bar arranged to be set in positions corresponding to each landing at which the car stops, means controllable from such landings for rocking said bar, an arm pivotally mounted on said bar and carrying brushes, 25 means normally acting to yieldingly maintain said brushes in contact with said contact-segments, and means for automatically rocking said arm to break said circuits when the car arrives at the position corresponding to the 30 position to which said bar is rocked, as and for the purpose set forth.

25. In an automatic elevator, a hoisting-motor, circuits therefor, a contact-disk, a rotatable bar adapted to be set to various positions corresponding to the various landings 35 at which the car stops, a brush-arm pivotally mounted on said bar, a flange formed on said arm, a stop on said disk for engaging said flange, and a rocking lever automatically actuated for engaging said brush-carrying arm and moving the same to break the motor-circuits, as and for the purpose set forth.

26. In an automatic elevator, a hoisting-motor, a counter-shaft driven therefrom, a 45 contact-carrying disk mounted on said counter-shaft and adapted to rotate therewith, said disk provided with a pin or projection, an arm loosely sleeved on said counter-shaft to rotate thereon, said arm adapted to be rotated 50 to varying positions according to the various landings at which the car stops, a brush-carrying arm pivotally mounted on said bar and normally held in position to complete the circuit of the motor, said arm provided with a 55 flange arranged to be engaged by the pin or projection on said disk, and an automatically-actuated lever arranged to engage said arm and rock the same to break the motor-circuits when the car reaches the particular landing 60 corresponding to the position of said bar, and means controllable from each floor for rocking said bar, as and for the purpose set forth.

27. In an elevator, a hoisting-motor, circuits for said motor, and means whereby part of 65 the operating-current which passes through

the armature of the motor is short-circuited across the field of the motor when the car is ascending, as and for the purpose set forth.

28. In an elevator, the combination of a hoisting-motor, electric circuits therefor, and 70 means whereby part of the operating-current which passes through the field of the motor will be short-circuited across the armature of the motor when the car is descending, substantially as described, as and for the purpose set forth. 75

29. In an elevator, the combination of a hoisting-motor, circuits therefor, means controllable from each landing for governing said motor, whereby said motor may be started 80 from each floor and will automatically stop when the car arrives at a predetermined floor, and means whereby part of the operating-current which passes through the armature of the motor will be short-circuited across the 85 field of the motor when the car is ascending, as and for the purpose set forth.

30. In an automatic elevator, the combination of a hoisting-motor, circuits therefor, means controllable from each landing for 90 starting the motor and automatically arresting the same when the car reaches a particular landing, and means whereby part of the operating-current which passes through the field of the motor will be short-circuited across 95 the armature of the motor when the car is descending, as and for the purpose set forth.

31. In an elevator, the combination with a hoisting-motor, circuits therefor, means whereby part of the current which passes 100 through the armature of the motor will be short-circuited across the field of the motor when the car is ascending, and means whereby part of the current which passes through the field of the motor will be short-circuited 105 across the armature of the motor when the car is descending, substantially as described, as and for the purpose set forth.

32. In an automatic elevator, a hoisting-motor, a controller for starting said motor and 110 arresting the same when the car reaches any predetermined landing, means for operating said controller, and means for locking said controller against reverse action while the motor is in motion, as and for the purpose set 115 forth.

33. In an automatic elevator, a hoisting-motor, a controller therefor, means operated from each landing for actuating said controller for starting the motor, means for automatically operating said controller to arrest the motor when the car arrives at any predetermined landing, and means for locking said controller against reverse action when the motor is once started, whereby the motor-circuits cannot be reversed while the motor is in operation, as and for the purpose set 125 forth.

34. In an automatic elevator, the combination with a hoisting-motor, of a controlling- 130

switch for said motor, said switch arranged when set, to start said motor and to automatically open when the car reaches any particular predetermined point, and means for 5 automatically locking said controller against reverse action while the motor is in operation, as and for the purpose set forth.

In witness whereof I have hereunto set my hand, this 5th day of March, 1898, in the presence of the subscribing witnesses.

HAROLD ROWNTREE.
